DESIGN FOR A SHOE HEEL

Frank Cleve, Jr., Kansas City, Mo.

Application February 28, 1945, Serial No. 118,180

Term of patent 7 years

(Cl. D7—5)

To all whom it may concern:

Be it known that I, Frank Cleve, Jr., a citizen of the United States, residing at Kansas City, in the county of Jackson and State of Missouri, have invented a new, original, and ornamental Design for a Shoe Heel, of which the following is a specification, reference being had to the accompanying drawing, forming a part thereof.

Fig. 1 is a face view of the shoe heel, showing my new design; and

Fig. 2 is a sectional view through the shoe heel, taken on line II—II of Fig. 1.

I claim:

The ornamental design for a shoe heel, as shown.

FRANK CLEVE, JR.
